METHOD OF BUILDING REINFORCED-CONCRETE AND COMPOSITE VESSELS.

1,367,986.

Specification of Letters Patent.

Patented Feb. 8, 1921.

Application filed June 24, 1918. Serial No. 241,512.

To all whom it may concern:

Be it known that we, GEORGE C. NEWTON and RALPH E. NEWTON, citizens of the United States of America, and residents of the city of Milwaukee, county of Milwaukee, and State of Wisconsin, have invented a new and useful Improvement in the Methods of Building Reinforced - Concrete and Composite Vessels.

10 We do hereby declare the following to be a full, clear, and exact description of the said invention such as will permit others skilled in the art to practise the same.

Our invention relates primarily to improved methods of building reinforced concrete and composite vessels and particularly vessels having reinforced concrete skins and precast or prefabricated ribs, cross frames, and stiffening members. In the past reinforced concrete vessels have been built with ribs and skin integral, being cast at one and the same time. There have also been attempts made to precast the ribs and attach the skin later by running skin reinforcing rods through eyes that project from the exterior of the ribs. All of these methods are open to serious limitations. They are expensive and very difficult and impracticable if not impossible for use commercially with 30 large vessels of molded form.

Our invention is designed to permit us to place the ribs in the final position they will occupy when the vessel is completed, to have the ribs act as alining, spacing, and holding members for the interior and exterior forms, and reinforcing and thus insure exactness of final result and enable us to dispense with the expensive shoring and other false work otherwise necessary to hold 40 the forms in place. Furthermore, the forms can be made in standard sections for repeated use. We are also enabled by our invention to form a much stronger bond between the ribs on the one hand and the skin, 45 keelson, and longitudinal beams on the other, and are enabled to place our reinforcing so as to give the maximum efficiency in taking up the strains in the skin, which cannot be done if its character and position is limited 50 as in other forms of rib construction. It is very desirable in vessels of this class which are not cast integral to so construct the vessel as to avoid lines of weakness where the different parts join, and our improved 55 method of construction enables us to entirely overcome this trouble. The points of at-

tachment between the ribs and longitudinal beams and between the ribs and skin are of strength as great as or greater than though the vessel were built integral and there is 60 no tendency of the vessel to break open at those points nor are there any construction joints left which are liable to such tendency.

It is also desirable in many cases to use a different grade and kind of concrete in 65 the ribs from that used in the skin as strength is more desired in the one place and water proof qualities in the other. This we are enabled to do by our method. We are also enabled where we use reinforced 70 concrete ribs to pour them in a horizontal position which has many points of advantage over any other method of construction, among which might be mentioned accuracy and cheapness of form construction, accessibility for placing and inspection of reinforcing, and absence of voids in the finished 75 product. The concrete may be placed around the skin reinforcing by any of the well known methods, preferably by pouring between molds.

The accompanying drawings illustrate our invention: Figure 1 is a transverse section through a ship constructed in accordance with our invention, showing in elevation a cross frame comprising ribs and deck beams, part of the concrete being broken away to show the reinforcing; Figs. 2, 3, 4, and 5 are detail sections of several forms of anchoring means for attaching the ribs to 90 the skin, all taken on the line 2—2 of Fig. 1; Figs. 6, 7, and 8 are detail sections, also on the line 2—2 of Fig. 1, showing the ribs with the forms held in position ready for pouring the concrete of the skin, and in 95 Figs. 6 and 7 showing also the cargo battens in place; Fig. 9 is a partial longitudinal section along the keelson, taken on the line 9—9 of Fig. 1, showing the ribs, floor, and bottom skin in cross-section; and Figs. 10 100 and 11 are sections through the keelson, on the line 10—10 of Fig. 9, showing more in detail the scheme of reinforcing and of attachment to the keelson, for two slightly different arrangements. Throughout the 105 drawings, like numerals refer to like parts.

A ship constructed in accordance with our invention has the usual main parts. There are a plurality of transverse ribs 1, and the upper ends of each transverse rib may be 110 connected by a transverse deck beam 2. The deck which rests on these transverse deck

beams may have any usual or suitable additional support, in the main not shown but often including fore-and-aft beams 3. A keel 4 may be provided, as shown in Figs. 1 and 10, or may be omitted, as shown in Fig. 11; and in either case a keelson 5 and longitudinal floor and side beams 6 are preferably provided. Suitable reinforcing 7 and 8 is provided for the ribs and deck beams respectively when they are made of concrete.

In accordance with our invention, a skin 9 of concrete, with suitable reinforcing 10 is supported by the ribs and abuts against their outer edges, but is constructed separately therefrom between forms held in place by the ribs, as hereinafter apparent. Usually, there is a floor 11 which rests on the keelson 5, floor beams 6, and the lower part of the ribs 1; and cargo battens 12 may be attached to the inner upright edges of the ribs 1. At the bilge there may be reinforcing 13.

The ribs 1 and the transverse deck beams 2 are cast preferably in horizontal position, 25 of concrete which is mixed for maximum strength without regard to water-proof qualities. When thus cast, they have partly embedded in them and projecting from their outer edges a plurality of temporary supporting members 14, for abutting against and spacing the exterior skin form, and also have partly embedded therein and projecting from their outer edges a number of stirrups 15, which form part of the reinforcing means and serve particularly as attaching means between the ribs and skin or between the transverse deck beams and deck. These stirrups may take a number of forms, as shown in Figs. 2, 3, 4, and 5, all of which 40 show the stirrups embedded in both the ribs and the skin. In Fig. 2, the stirrup 15 is shown as a simple metal bar which runs around the reinforcing bars 7 of the rib 1 and has its free ends projecting from the 45 outer edge of the rib, so that when the rib is set in place such ends may be bent into the plane of the skin, so that they will lie parallel to and near the exterior of the skin 9, and will cross each other. By having 50 these ends cross, additional anchorage is given to the skin. In the arrangement shown in Fig. 3, the ends 15' of the reinforcing stirrup 15 are not so long as in Fig. 2, but are attached to a skin-reinforcing bar 55 or plate 16 in any suitable manner, as by butt-welding, riveting, or bolting. In the arrangement shown in Fig. 4, the rod which runs around the reinforcing bars is closed on itself; and a separate rod 15 projects 60 from the edge of the rib, and is provided at its inner or embedded end with an anchor plate or bar 17, and at its outer projecting end is attached to the skin-reinforcing bar or plate 16 in the same manner as in the arrangement shown in Fig. 3. In the ar-

rangement shown in Fig. 5, the rod which runs around the reinforcing bar 7 is closed on itself as in the arrangement shown in Fig. 4, and two attaching rods 15, with suitable anchorages in the rib project from the rib with rather long projecting ends, as in the arrangement in Fig. 2, and these projecting ends are bent across each other to lie in the plane of the skin 9 near the exterior surface thereof. All these forms of stirrups have members which are embedded in and project from the outer edge of the rib, and are either themselves bent into the plane of the skin, or attached to reinforcing members lying in such plane.

After the ribs and transverse deck beams have been cast in horizontal positions and hardened, they are set up in the positions they are to occupy in the ship, the projecting ends of the stirrups 15 are bent into the plane of the proposed skin or are attached to skin-reinforcing plates 16, and the forms for the skin are put in place. These forms are attached to and supported by the ribs. The arrangement of forms is shown in Figs. 6, 7, and 8. The edges of the interior skin forms abut against the side faces of the ribs 1. The inner face of the exterior skin form 19 abuts against the temporary supporting members 14 which are cast in and project from the edges of the ribs. The inner skin form 18 is spaced from the exterior skin form 19 in any usual or convenient manner. Thus these forms are definitely located with respect to the rib. Both the interior and exterior skin forms 18 and 19 are backed by a series of studding 20, in turn backed by girts 21 extending transversely thereof. The girts for the outer skin form are held in position by bolts 22 and nuts 23, the inner ends of these bolts being threaded and cooperating with internally threaded inserts 24, which are cast in the outer edges of the ribs 1 as the latter are poured and are conveniently flush with such edges. By this arrangement, the bolts 22 can readily be withdrawn after they have served their purpose of holding the forms. The girts 21 for the inner skin form have their ends, which are close against the ribs 1, held in place by nailing pieces 26 which in the arrangement shown in Fig. 6 are fastened to the side faces of the ribs 1 by bolts 25 passing transversely through such ribs. These nailing pieces 26 serve the double purpose of holding the girts 21 in place and of providing nailing strips for the cargo battens 12, for obviously these cargo battens are not attached until after the skin has been poured and the forms (including the studding and the girts) have been entirely removed. When desired, the nailing pieces 26 which are used for holding the studs 21 may be removed, and new pieces substituted for the attachment of the cargo battens 12. The

flooring 11, if made of wood, may be attached to the nailing pieces 26 in the same manner. Instead of the nailing pieces 26, held in place by the through-bolts 25, the 5 pieces for holding the ends of the girts 21 for the interior skin form may be fastened to the ribs by bolts 30 screwed into inserts 31 cast in the side faces of such ribs, as shown in Fig. 7. The cargo battens 12 and 10 the flooring 11 may be held against the inside edges of the ribs by similar bolts 30 and inserts 31, but these inserts and bolts are usually not in the same plane transverse to the rib as are the bolts and inserts for the 15 girt-holding pieces, although they are so shown in Fig. 7. When the skin forms 18 and 19 have been properly placed and braced, as described, and the skin reinforcements placed, the concrete for the skin is 20 poured between such skin forms, and allowed to harden; and then the forms are removed.

When the ribs 1 are of concrete, as shown in Figs. 6 and 7, additional strength is given 25 to the joint between the rib 1 and the skin by having notches 28 cast in the rib and corresponding bevels or notches 28' on the interior skin forms 18 where they abut against such rib, so that in casting the skin there are 30 formed lugs or keys 29 which partially surround and grip between them the projecting end of the rib 1.

The ribs 1 may be made of rolled or fabricated metal, as shown in Fig. 8, instead of 35 being made of concrete, as shown in Figs. 6 and 7. In such case, the skin forms 18 and 19 are also held in proper position by the ribs. Both skin forms have their backing of studding and girts, as with concrete ribs; 40 the girts 21 for the outer skin forms are held, as before, by bolts 22, which in this case pass through the flanges of the metal rib 1, and the girts 21 for the interior skin forms are held in place by removable blocks 27 between such 45 girts and the flanges of the ribs. The skin-attaching members 15 are in this case conveniently fastened to the flanges of the ribs 1, as by being passed through suitable holes near the edges of such flanges, and are bent 50 into the plane of the skin, as shown in Fig. 8 and in substantially the same way as indicated for the concrete ribs in Figs. 2 and 5.

The keel 4 when it is provided, and with it if desired the entire keelson 5 when its lower 55 portion forms the keel 4, is preferably cast integral with the skin 9, so as to avoid any joints in the surface exposed to the water; the keelson may be cast integral with the skin even when its lower part does not form a 60 keel. This is clear from Figs. 9, 10, and 11. As shown in such figures, the ribs 1 cross the keelson. Ordinarily, the ribs will be continuous across the plane of the keelson, so that the keelson will not be continuous 65 through the ribs, though it may project

above the ribs and be continuous over them, as is clear from Fig. 11. The rib reinforcements 7 extend transversely through the plane of the keelson, being embedded in the concrete forming the ribs. In casting the 70 ribs, part of the keelson reinforcements 32 may be cast in them; or holes may be left in the ribs through which the keelson reinforcements 32 may be passed; this, however, is not necessary for such of the keelson reinforcements as are located in that portion of the keelson which may project above the ribs 75 1, as shown in Fig. 11, or below the ribs, as shown in Fig. 10.

In practice, the ribs 1 and transverse deck 80 beams 2 are pre-cast or pre-fabricated, according as they are of concrete or steel. If of concrete, they are preferably cast in horizontal position, as has been stated, with the members 14, 15, 24, and 30 (if the members 30 85 are used,) and part of the keelson reinforcements 32 cast in them, as stated. The ribs are set up in place, and may have the transverse deck beams or other deck supports attached to them. The stirrups 15 are then 90 bent into the positions indicated in the drawings, or skin-reinforcing members are attached to them. Then the forms are set up in proper position with relation to the ribs, being supported by the ribs, and the reinforcements are put in place; and the skin, keelson, and longitudinal side and floor beams are poured to embed the reinforcements, preferably in one continuous operation 95 up to the level of the lower portion of 100 the deck in order to avoid construction joints in the outer surface of the ship. As the concrete of the skin and keelson hardens, it fastens these parts to the ribs as securely as though they were poured integral with the 105 ribs. The concrete for the skin is preferably mixed as a water-proof concrete, so that it is different in its nature from the concrete of the ribs. This is made possible by the fact that the ribs and skin are poured separately. 110 If a concrete deck or concrete fore-and-aft deck beams are used, they can be cast in a subsequent continuous operation; or if preferred, they may be cast in the same continuous operation with the skin, in which latter case the entire ship is poured integral 115 with the exception of the ribs.

Having thus described our invention we claim:

1. The method of building vessels with reinforced concrete skins, which consists in casting or fabricating ribs with form holding and spacing and skin reinforcing and attaching means as a part thereof, attaching forms to said holding means, and pouring 120 concrete between such forms.

2. The method of attaching ribs to a reinforced concrete vessel skin, which consists in casting or fabricating ribs with skin reinforcing and attaching means as a part 125 130

thereof with the free ends thereof extending outwardly therefrom, bending said ends out of the plane of the ribs and into the plane of the intended skin, and pouring the skin concrete to embed such ends.

3. The method of attaching ribs to a reinforced concrete vessel skin, which consists in casting ribs with skin reinforcing and attaching means embedded therein and having 10 free ends extending outwardly therefrom, bending said ends so as to join with the skin reinforcing, and pouring the skin concrete to embed such ends.

4. The method of attaching prefabricated

or precast ribs to a reinforced concrete vessel skin, which consists in so constructing the ribs and interior skin forms as to form grooves in which the skin concrete will set to form lugs or shoulders partially surrounding the rib, and pouring the skin concrete between such forms and into such grooves to form said lugs or shoulders.

GEORGE C. NEWTON,
RALPH E. NEWTON.
